[57] CLAIM

The ornamental design for a sheet dispenser, as shown and described.

DESCRIPTION

FIG. 1 is a top front perspective view of a sheet dispenser showing our new design;
FIG. 2 is a front elevational view;
FIG. 3 is a rear elevational view;
FIG. 4 is a left side elevational view, the right side being a mirror image thereof;
FIG. 5 is a top plan view;
FIG. 6 is a bottom plan view;
FIG. 7 is a top front perspective view with the cover member removed for convenience of illustration;
FIG. 8 is a front elevational view of FIG. 7;
FIG. 9 is a rear elevational view of FIG. 7;
FIG. 10 is a left side elevational view of FIG. 7, the right side being a mirror image thereof;
FIG. 11 is a top plan view of FIG. 7; and,
FIG. 12 is a bottom plan view of FIG. 7.
